DRIVING GEAR FOR PRINTING PRESSES

Walter Rockstroh, Dresden, Germany

Application May 3, 1932, Serial No. 608,961, and
in Germany September 28, 1931

11 Claims. (Cl. 101—250)

This invention relates to improvements in driving gear for printing presses and has particular but not exclusive reference to flat bed machines.

Prior to the present invention it has been customary to mount the elements of the gear for driving flat bed printing presses individually in the supporting frame of the press, so that a separate mounting within the supporting frame was necessary for each of the shafts of the drive.

Printing machines have also been constructed in which a part of the drive is mounted outside the wall of the machine. In neither of these types of machine, however, can the driving mechanism as a whole be detached from the machine, since each of the shafts is mounted separately in the supporting frame and must therefore be detached separately from the machine.

The present invention has amongst its objects to obviate this disadvantage and with this and other ends in view all the parts of the driving gear serving to impart motion to the component parts of a printing machine are encased in a separate gear box.

The gear box is preferably detachably mounted and may be situated within or without the supporting frame of the press.

In a device according to the present invention the gear box controls the movements of all the movable parts of the press, whether the rotary motion for driving the continuously rotating impression cylinder or that for driving the one-revolution control shaft which produces the timed movements. Each of the shafts which serve to impart motion to a part of the press is detachably connected to the corresponding driven member, for example, by a simple coupling or by toothed wheels. The driving gear can be of any convenient type, there being many known constructions which can be inserted in a sub-frame such as is provided according to the invention.

In order that a better understanding of the invention may be obtained reference will now be made to the accompanying drawing, wherein:—

Figure 1 shows in side elevation one constructional example of a printing press according to the invention.

Figure 2 is a sectional plan view of the construction shown in Figure 1.

The supporting frame of the printing press illustrated is constructed in two parts, a lower part 1 and an upper part 2, the sub-frame 3 being bolted or otherwise detachably mounted on the lower part 1. The upper part 2 which is

suitably mounted on the lower part 1 carries the tracks for the printing carriage 4. In the construction shown, the shafts 5 on which the wheels 6 are mounted are employed for imparting motion to the carriage 4. The shaft 7 makes a uniform rotary movement and is therefore used for driving the impression cylinder 8. The shaft 9 rotates rapidly and may be employed for driving, for instance, the rapidly rotating feed drums 11 of the feed apparatus which delivers the paper or other material to be printed to the press. The driving motor 10 is so mounted on the gear box 3, that it does not require any special support in the frame of the press.

A driving gear such as described has many advantages over the constructions heretofore proposed; for example, the individual mounting of numerous shafts in the frame is obviated. The gear boxes may be manufactured by mass production and they may be so constructed that one gear box can be used for several sizes of machines, and furthermore they may be inserted complete in the machine. The driving gear may also be located in a place within the machine where it neither weakens the frame nor makes the machine longer, as for example the known driving device of stop cylinder machines. The gear requires little attention because it can run in oil and can be detached from the machine without difficulty.

I claim:—

1. A printing press, comprising an impression member and a printing member, means for feeding the material to be printed between them, a main frame for said press, a subsidiary frame detachably mounted on and carried by said main frame, and driving gear for the press housed in said subsidiary frame.

2. A printing press, comprising an impression member and a printing member, means for feeding the material to be printed between them, a main frame for said press, a subsidiary frame removably carried in said main frame, and driving gear for the press housed in said subsidiary frame and removable therewith.

3. A printing press having the usual co-operating members between which the material to be printed is pressed, comprising the combination with the frame work of the press, of a cradle detachably mounted therein, and driving mechanism for said press supported in said cradle and removable en bloc therewith.

4. A flat bed printing press, comprising the combination of a frame of said press, a printing carriage reciprocatable thereon, an impression

- cylinder for co-operating with said carriage, a sub-frame removably attached to the frame of the press, and driving mechanism for said carriage and cylinder carried by said sub-frame and removable as a unit therewith. 5
5. In a printing press having the usual movable co-operating members between which the printing is effected, the combination of a machine bed on which said members are carried, a sub-frame 10 removably attached to the bed, and driving gear for the said members and one electric motor coupled to said gear all carried upon the sub-frame and forming a unitary structure therewith. 15
6. In a printing press, a machine frame, means for effecting the printing and means for feeding the material to be printed thereto, a gear-box detachably mounted on said frame, and driving gear for said means contained within the gear box. 20
7. A flat-bed printing press comprising a supporting frame, a printing carriage reciprocatable thereon, an impression cylinder for co-operating with said carriage, feed mechanism 25 for delivering the material to be printed to said press, a sub-frame detachably mounted within the said supporting frame and driving mechanism for said carriage, cylinder and feed mechanism carried by said sub-frame and removable 30 as a unit therewith. 35
8. A flat-bed printing press comprising a supporting frame, a printing carriage reciprocatable thereon, an impression cylinder for co-operating with said carriage, feed mechanism for delivering material to be printed to said press, a sub-frame detachably mounted within said support- 40

- ing frame, and a driving motor for imparting motion to the said carriage, cylinder and feed mechanism carried by said sub-frame and forming a unitary structure therewith. 80
9. A flat-bed printing press comprising a supporting frame, a printing carriage reciprocatable thereon, an impression cylinder, feed mechanism for delivering the material to be printed to said press, a sub-frame detachably mounted in said supporting frame, driving mechanism for the said carriage, cylinder and feed mechanism carried by said sub-frame and removable as a unit therewith and detachable couplings extending from said driving mechanism to the said carriage, cylinder and feed mechanism for imparting motion thereto. 85
10. A flat-bed printing press comprising a supporting frame, a printing carriage reciprocatable thereon, an impression cylinder, feed mechanism for delivering the material to be printed to said press, a sub-frame detachably mounted in said supporting frame, driving mechanism for the said carriage, cylinder and feed mechanism carried by said sub-frame and removable as a unit therewith and toothed 90 wheels for transmitting the drive from said driving mechanism to said carriage, cylinder and feed mechanism for imparting motion thereto. 95
11. A printing press comprising an impression member and a printing member, means for feeding the material to be printed between them, a frame for said press, a gear-box removably attached to said frame and driving gear for the press housed within said gear box. 100
